SAFETY SWITCH FOR STRANDING MACHINES

Carl O. Bruestle and Hugo Wilken, Rahway, N. J.,
assignors to Synero Machine Company, Perth
Amboy, N. J., a corporation of New Jersey

Application August 18, 1948, Serial No. 44,809

9 Claims. (Cl. 57—81)

1

The present invention relates to a switch for utilization particularly with a stranding machine. Such machines twist together a plurality of strands of wire, hemp or the like and it is essential that the machine be brought to a stop in the event that one of the strands breaks.

The present invention accomplishes the object mentioned above in a very simple manner and is so constructed as to be operable even when the tension on the strands is very small.

It is an object of the invention to provide a switch to stop a stranding machine upon the breakage of one or more of the strands which are being twisted.

It is another object of the invention to provide such a switch which will operate upon a very small differential in the tension applied to the strand cable as a whole.

It is another object of the invention to provide such a switch which is economically built and which is rugged and capable of reliably performing its function for long periods of time.

Other objects and features of the invention will appear when the following description is considered in connection with the annexed drawings in which—

Figure 1 is a side elevation of a switch mechanism of our invention;

Figure 2 is an end elevation of the device of Figure 1, the view being taken from the right; and

Figure 3 is a top plan view of the switch of Figures 1 and 2.

Referring now to the drawings, 10 represents a supporting plate, the sides 11 and 12 of which are bent forwardly to form supports for various parts of the apparatus. Likewise, the base of plate 10 is bent forwardly and upwardly as indicated at 13 and 14, respectively, to form additional supports for operating parts of the device as well as to form, together with a cover 15, an enclosure for the major portion of the device.

Mounted in an upward extension 16 of the plate 10 is a stub shaft 17 on which two pulleys 18 and 20 are rotatably supported.

Mounted in the plate 10 and the bent-over upwardly extending portion 14 thereof is a pin or shaft 21 on which is a bearing 22 which in turn supports a generally rectangular block 23. Fixed to the block 23 as by welding is a channel member 24 which thus forms a pivoted arm. At the upper end of the arm 24 there is mounted a second stub shaft 25, carrying the two rollers 26 and 27.

The one arm of the angle from which member

24 is formed is provided with a slot 28 into which extends the end of a horizontally extending screw 30, which screw is threadedly mounted in a block 31 welded in an opening in the forwardly extending left hand portion 11 of the supporting plate 10. Screw 31 is provided with a washer 32 on a shouldered portion thereof and a spring 33 extends from washer 32 to a second washer 34 which bears against the forwardly extending portion of the angle from which arm 24 is formed. Also mounted in the angle portion mentioned is an adjustable screw 35 which, when the arm is in the position shown, bears against the contact point 36 of a microswitch 37, which switch is fastened to the supporting plate 10 in any suitable manner.

A cable from a wire stranding machine is indicated at 38. This cable passes beneath the pulley 18, thence beneath the pulley 26 and from the pulley 26 along the top thereof to the top of pulley 20, thence around that pulley under pulley 27 and around pulley 27 to the usual drawing capstan 40. Due to the mounting of the pulleys 26 and 27 on the spring pressed arm 24, it is possible to cause the arm to move in clockwise direction as seen in Figure 1 when the tension on the arm 24, due to the passage of the wire over the pulleys 26 and 27 thereon, becomes less than the pressure exerted by the spring 33. Since the microswitch 37 is opened by movement of the arm 24 to the position shown in Figure 1, the circuit to the driving motor of the strander, as well as the capstan 40, will be broken immediately upon the arm 24 coming into the position shown in Figure 1. Pressure exerted by spring 33 may obviously be varied by adjustment of the position of screw 30. This pressure is determined in accordance with the tension desired on the wire strands as modified by the pulley arrangement.

In a particular instance, three strands are made into a cable and a tension of one pound per strand is maintained. Utilizing the particular pulley arrangement disclosed, a force of approximately twelve pounds acts upon the arm 24 to draw it to the left or in a counterclockwise direction. In this instance the screw 30 is adjusted so that the spring 33 exerts a pressure of approximately nine pounds in a clockwise direction. Thus, while the machine is operating normally, the pivoted switch arm 24 lies to the left and the contacts of the microswitch are closed. If a strand of wire breaks, the tension exerted on the arm 24 by the cable 38 drops to eight pounds and consequently spring 33 takes control and moves the arm into

the position shown in Figure 1 opening micro-switch 37 and stopping the stranding machine.

It will be obvious that the stationary pulley may be omitted and the cable led directly from the twisting die around a single pulley mounted on the pivoted arm and thence to the drawing capstan. It will likewise be obvious that by increasing the number of pulleys and consequently increasing the number of wire wraps the tension may be multiplied as many times as is desired. Also, by adjusting the spring 33 the differential upon which the switch will be actuated may be modified. Consequently, while we have described the preferred embodiment of our invention it will be understood that modifications may be made within the scope thereof. We wish therefore to be limited not by the foregoing description which was given solely for purposes of illustration but only by the claims granted us.

What is claimed is:

1. In a safety switch structure for wire stranding machines and adapted to be operationally located between the twisting die and the drawing capstan of the stranding machine, in combination, a pivoted arm, a pulley on said pivoted arm, said pulley being adapted to have a stranded cable wrapped around it in advance of the drawing capstan, an adjustable spring bearing against said pivoted arm and a switch mounted adjacent said pivoted arm adapted to be operated by movement of said swinging arm resulting from a decrease in tension on the cable.

2. A device as claimed in claim 1, characterized in that a shouldered screw is mounted adjacent said pivoted arm, said screw being provided with a pair of washers said adjustable spring extends between said pair of washers, one of said washers seating on the shoulder of said screw and the other against said pivoted arm, said screw being threadedly mounted in a support to thereby adjust the pressure exerted by said spring.

3. A device as claimed in claim 1, characterized in that said pivoted arm is provided with a screw threadedly mounted therein, said screw serving to make contact with said switch to open the switch.

4. A device as claimed in claim 1, characterized in that a shouldered screw is mounted adjacent said pivoted arm, said screw being provided with a pair of washers said adjustable spring extends between said pair of washers, one of said washers seating on the shoulder of said screw, said screw being threadedly mounted to thereby adjust the pressure exerted by said spring, said pivoted arm being provided with a screw threadedly mounted therein, said screw serving to make contact with said switch to open the switch.

5. In a safety switch for wire stranding machines and the like, in combination, at least one pulley on a fixed axis, a plurality of pulleys co-operating with said one pulley, a pivoted arm on which said second mentioned pulleys are mounted for movement toward and away from said first

mentioned pulley, said pulleys being adapted to have a stranded cable wrapped about them in advance of the drawing capstan, an adjustable spring bearing against said pivoted arm and a switch mounted adjacent said swinging arm and adapted to be operated by movement of said swinging arm resulting from a decrease of tension on the cable.

6. A device as claimed in claim 5, characterized in that a shouldered screw is mounted adjacent said pivoted arm, said screw being provided with a pair of washers said adjustable spring extends between said pair of washers, one of said washers seating on the shoulder of said screw and the other against said pivoted arm, said screw being threadedly mounted to thereby adjust the pressure exerted by said spring.

7. A device as claimed in claim 5, characterized in that said pivoted arm is provided with a screw threadedly mounted therein, said screw serving to make contact with said switch to open the switch.

8. A device as claimed in claim 5, characterized in that a shouldered screw is mounted adjacent said pivoted arm, said screw being provided with a pair of washers said adjustable spring extends between said pair of washers, one of said washers seating on the shoulder of said screw and the other against said pivoted arm, said screw being threadedly mounted to thereby adjust the pressure exerted by said spring, said pivoted arm being provided with a screw threadedly mounted therein, said screw serving to make contact with said switch to open the switch.

9. In a safety switch for wire stranding machines and the like, in combination, a plurality of pulleys rotatably mounted on a support, a second plurality of pulleys mounted in line with said first mentioned pulleys, said second mentioned pulleys being mounted on the end of a pivoted arm, said first and second mentioned pulleys being adapted to receive a number of wraps of cable from the stranding machine, which cable is under tension exerted by a drawing capstan, means for exerting adjustable spring pressure against said pivoted arm in a direction opposite to the tension exerted by the wraps of cable about said pulleys, and a switch operated by said pivoted arm upon a decrease in tension in the cable.
